UNITED STATES PATENT OFFICE.

LEROY P. CLUTTER, OF BEAVER FALLS, PENNSYLVANIA.

EXCAVATING-MACHINE.

1,288,514.

Specification of Letters Patent. Patented Dec. 24, 1918.

Application filed August 29, 1913. Serial No. 787,312.

To all whom it may concern:

Be it known that I, LEROY P. CLUTTER, a citizen of the United States of America, residing at Beaver Falls, in the county of Beaver and State of Pennsylvania, have invented certain new and useful Improvements in Excavating-Machines, of which the following is a specification, reference being had therein to the accompanying drawing.

10 This invention relates to excavating machines, and the primary object of my invention is to provide a self-propelled excavating machine with novel means, as hereinafter set forth, for easily and quickly controlling the excavating operations of the machine, whereby the work can be expeditiously and economically performed.

Another object of this invention is to provide a machine of the above type with a novel boom that can be simultaneously moved in different directions, and the excavating bucket projected beyond the boom to that extent that a piece of work can be performed or considerable excavating accomplished without repeatedly moving the machine.

A further object of this invention is to provide a self-propelled excavator that presents a rigid and durable structure capable of withstanding the rough usage to which machines of this type are subjected, particularly when rock, shale and other indurate material is encountered.

The invention in its broadest aspect involves positive and reliable means for controlling the scooping and loading of the excavator bucket and to this end I have devised a novel clutch and brake mechanism, together with structural elements which 40 when combined provide a safe and highly efficient traction excavator.

The machine as invented comprehends the combination or assemblage of coöperating instrumentalities, which, broadly considered, 45 are new as a general combination, and also comprehends various improvements in the construction of the elements themselves, and various subcombinations of selected elements.

50 The principal elements of the invention, namely, a vehicle; a turning head and its connections; a boom and its connections; a clutch mechanism, and a brake mechanism, will be hereinafter separably and specifically 55 described in detail together with their asso-

ciated coöperating appliances and the objects accomplished from such a combination of elements.

In the drawings:

Figure 1 is a side elevation of the excavating machine, showing the shovel in an extended position by dotted lines,

Fig. 2 is an enlarged side elevation of a portion of the vehicle, particularly the boom and its connections,

Fig. 3 is a perspective view of the boom and its connections,

Fig. 4 is an enlarged plan of the clutch and brake mechanisms,

Fig. 5 is a cross sectional view of the same.

Figs. 6 and 7 are detail elevations of the clutch and brake mechanisms,

Fig. 8 is an enlarged sectional view of a controlling mechanism, and

Fig. 9 is a longitudinal sectional view of the same.

In describing my invention by aid of the drawings above referred to I desire to point out that I intend said views as merely illustrative of an example whereby my invention may be applied in practice, and I do not limit my claims to the precise arrangement and construction of parts indicated. The following description is therefore to be construed broadly as including substitute arrangements and constructions which are the obvious equivalent of those shown.

Considering the various elements of the invention in detail and in their order as enumerated above; the vehicle comprises longitudinal beams 1 and 2 connected by transverse girders or braces 3 and 4. These elements constitute the frame of the machine and said frame is supported by the forward wheels 5 and rear wheels 6, said 90 rear wheels having large gear wheels 7 meshing with small gear wheels 8 driven from an engine 9 located upon the rear end of the frame. The engine 9 receives steam from a boiler 10 and in lieu of the engine 100 and boiler any suitable operating means can be resorted to. The engine 9 can be used for moving the machine to a locality where work is to be performed and any steering mechanism can be used in connection with 105 the forward truck of the vehicle for guiding the machine while being moved.

Turning head and its connections.

The frame of the vehicle is provided with 110

uprights 11 and 12, the former being located centrally of the forward end of the machine and in parallelism. See Figs 3 and 4. The uprights 11 are braced by angularly disposed braces 13 and the upper ends thereof are connected by diverging beams 14 to a transverse beam 15 connecting the uprights 12 which are located at the sides of the machine and intermediate the ends of the frame. The upper ends of the uprights 11 are provided with a forwardly extending bearing 16 and vertically alining with this bearing is a bearing 17 carried by the girder 3. Swiveled upon the bearings 16 and 17 by pins 18 are connections 19 and 20 supporting a mast 21 that is preferably made of channel bars arranged in parallelism. The pin of the connection 19 revolvably supports a transverse frame 22 of a circular turning head 23, said head being made of channel bars in order to form a horizontal grooved wheel to the periphery of which is attached by angle brackets 24 or other fastening means the ends of a cable 25. The cable 25 extends rearwardly and has a few convolutions upon a horizontal flanged wheel 26, carried by the upper end of a vertical shaft 27 journaled in bearings 28 and 29 provided therefor, the former being carried by the beam 15 and the latter located upon a transverse girder of the machine frame.

The turning head is braced by angle bars 30 and 31, the latter being secured upon the forward part of the turning head and having its ends protruding from the periphery of said head, whereby angularly disposed connecting rods 32 can be connected to said turning head. The turning head is also braced relatively to the mast 21 by angularly disposed braces 33.

The boom and its connections.

The lower end of the mast 21 has a transverse pivot pin 34 for the bearings 35 of a boom 36. The boom 36 is preferably made of two parallel channel bars suitably connected together. The outer end of the boom has bearings 37 and adjacent to the outer end of said boom are brackets 38. Connected to said bearings and said brackets are V-shaped frames 39 supporting a revolvable pulley 40 over which passes a cable 41. One end of the cable is attached to a pin 42 connecting the rods 32 of the turning head. The opposite end of the cable is connected to a pivoted block 43 carried by the outer end of an arm 44 that has the lower end thereof pivotally connected, as at 45 to the connection 20. The arm 44 is preferably made of two parallel bars and the block 43 of said arm is connected to the end of the cable 46 that passes over a revolvable sheave 47, revolvably mounted between the channel bars forming the mast 21. The cable 46

passes under a revolvable sheave 48 revolvably mounted between the channel bars forming the upright 11 and said cable is moved through the medium of a clutch mechanism that will be hereinafter considered.

Pivotedly connected to the upper end of the arm 44 by a transverse pin 49 is a yoke 50, said yoke providing clearance for the boom 36. The yoke 50 has the lower end thereof connected as at 51 to a bucket or scoop 52 and said yoke is rigidly held relatively to the bucket by angularly disposed braces 53. The bucket 52 is of the ordinary and well known type having a drop door 54 and a scoop 55, the scoop 55 being connected by a stirrup 56 to the end of a cable 57, said cable passing upwardly over a sheave 58 revolvably mounted between the bearings 37 of the boom 36. The cable 57 extends downwardly and is trained under a sheave 59 revolvably mounted between parallel bars forming the mast 21. The cable passes upwardly over a revolvable sheave 60 associated with the sheave 48 of the upright 11 and the operation of this cable will be herein-after referred to in connection with the clutch mechanism and the general operation of the machine.

Clutch mechanism.

The uprights 11 and 12 are connected by longitudinal frames 61 and said frames are connected to the beams 1 and 2 by supports 62. Mounted upon the frames 61 is a set of bearings 63 and journaled in said bearings 100 is a transverse shaft 64. The shaft 64, adjacent to one end thereof, has a sprocket wheel 65 and trained over said sprocket wheel is a sprocket chain 66 that extends to the engine 9 whereby the shaft 64 is revolved when the engine 9 is placed in operation. The wheel 65 and the chain 66 represent one form of transmission for imparting movement to the shaft 64.

Loosely mounted upon the shaft 64 are 110 the confronting conical-shaped beveled gear wheels 67 and 68, said wheels being held against longitudinal movement upon said shaft by collars 69. Slidably keyed upon the shaft 64 and adapted to rotate therewith is a clutch member 70 having the ends thereof provided with conical-shaped clutch heads 71 and 72 that are adapted to be alternately shifted into engagement with the gear wheels 68 and 67 respectively. The 120 clutch heads 71 and 72 are adapted to enter the gear wheels and frictionally engage the same whereby either gear wheel can be made to revolve in unison with the shaft 64.

Loosely mounted upon the clutch member 125 70 is a two-part shifting member 73 that is trunnioned in a yoke 74, carried by the upper end of a lever 75 pivotally connected, as at 76 to a bracket 77, carried by the beam 1. The lower end of the lever 75 is bifur-

cated, as at 78 and pivotally connected by a link 79 to a bell crank 80 that is pivotally connected, as at 81 to a bracket 82 carried by the beam 1. The bell crank 80 is pivotally connected, as at 83 to a link 84 that extends upwardly through an opening 85 provided therefor in a platform 86. The platform 86 is supported by angle brackets 87, carried by the outer side of the beam 1. The link 84 is pivotally connected, as at 88 to one end of a treadle 89, said treadle being pivotally connected, as at 90 to a bearing 91, carried by the platform 86. The opposite end of the treadle is pivotally connected, as at 92 to a depending rod 93 that extends through an opening 94 provided therefor in the platform 86. The lower end of the rod 93 has a nut 95 and a washer 96 and encircling said rod, between the washer 96 and the bottom side of the platform 86, is a coiled spring 97. This spring is employed to hold the treadle normally horizontal or in an inactive position. When the forward end of the treadle is lowered the clutch head 71 is shifted into the gear wheel 68 and when the rear end of the treadle is lowered the clutch head is shifted into engagement with the gear wheel 67. The weight of the link 84 is sufficient in one instance to 20 store the treadle 89 to a horizontal position and in the other instance the spring 97 accomplishes the same result.

Meshing with the gear wheels 68 and 67 is a beveled gear wheel 98 mounted upon the end of a shaft 99 journaled in bearings 100 and 101, carried by transverse braces 102 connecting the frames 61 and the uprights 12. The brace 102 connecting the uprights 12 (see Fig. 4) has a vertical bearing 103 for the shaft 27 and mounted upon said shaft is a worm wheel 104 meshing with a worm 105 of the shaft 99. The elements 98 to 105 inclusive represent a conventional form of transmission for placing the turning head 23 in operation and by having the gear wheel 98 meshing with both of the gear wheels 67 and 68 it is possible to turn the head 23 clockwise or counter-clockwise, such movement being controlled by the treadle 89 after the engine 9 has been placed in operation. With the clutch member 70 intermediate the gears 67 and 68, that is, out of engagement with both wheels, said wheels and the transmission of the turning head 23 remain inactive while the shaft 64 is revolving.

Mounted upon the frame 61 is another set of bearings 106 and journaled in said bearings is a transverse shaft 107 having a large gear wheel 108 adjacent to one end thereof. This large gear wheel meshes with a small gear wheel 109 mounted on the shaft 64.

Loosely mounted upon the shaft 107 are drums 110 and 111. The cable 46 is attached to and wound upon the drum 111 and the cable 57 is attached to and wound upon the

drum 110. The drums 110 and 111 have peripheral flanges 112 to retain said cables upon said drums and said drums are hollow or in the form of shells having short hubs 113 providing clearance for gear wheels 114 that are keyed or otherwise mounted upon the shaft 107 within the drums 110 and 111. The outer ends of the drums 110 and 111 have the inner walls thereof provided with circular racks 115 and the outer ends of said drums have radiating spokes 116 supporting brake wheels 117 and 118, said brake wheels being V-shaped in cross section.

Loosely mounted upon the shaft 107 and at the outer sides of the gear wheels 114 are the hubs 119 of brake wheels 120 and 121. The spokes 122 of said brake wheels support revoluble pinions 123 (see Figs. 5 and 6), said pinions meshing with the gear wheels 114 and the racks 115 of the drums 110 and 111.

Brake mechanism.

The beams 1 and 2 of the vehicle frame are connected by an angularly disposed transverse angle bar 124 and adjustably connected or anchored to said bar, as at 125 are the ends of flexible brake bands 126 that extend over the brake wheels 117, 118, 120 and 121, said brake bands having shoes 127 to engage in the grooves of said brake wheels.

The beams 1 and 2 of the vehicle frame are provided with transversely alining bearings 128 and journaled in said bearings is a rock shaft 129. One end of the shaft protrudes above the platform 86 and has the extreme end thereof provided with an operating lever 130. The lever 130 can be swung to rock said shaft and said lever is held in adjusted position through the medium of a segment rack 131, carried by the frame 61 and a latch 132, carried by said lever. The elements 130 to 132 inclusive are constructed upon the principle of a throttle that can be locked in a desired position.

The rock shaft 129 has cranks 133 and 134 disposed at substantially right angles with relation to each other. The crank 133 is connected by a link 135 to the brake band 126 of the wheel 118, and the crank 134 is connected by a link 136 to the brake band 126 of the wheel 121. In consequence of this arrangement the movement of the rock shaft 129 in one direction applies a brake band to one of the wheels and releases the other brake band and vice versa.

Loosely mounted upon the rock shaft 129 is a sleeve 137 and the outer end of said sleeve has a lever 138 similar to the lever 130. The lever 138 has a rack 139 independent of the rack 131 whereby the lever 138 can be locked in adjusted position.

The inner end of the sleeve 137 is provided with cranks 140 and 141, connected, similar

to the cranks 133 and 134, to the brake bands 126 of the brake wheels 120 and 117 respectively.

Operation.

5 In operation, an operator or attendant of the machine upon the platform 86 has the treadle 89 and the levers 130 and 138 at his command after the engine 9 has been started 10 and it is through the medium of the treadle actuated clutch member 70 that the operation of the turning head and the movement of the boom 36 and the bucket 52 is controlled. The operation of the drum 111 controls the raising and lowering of the boom 36 while the operation of the drum 110 controls the movement of the bucket 52 relatively to said boom. By connecting the cable 41 to the arm 44, the bucket 52 is extended or retracted simultaneously with the raising and lowering of the outer end of the boom 36 and it is possible, while these operations are in force to swing the boom 36 from one side of the machine to the other 15 through the medium of the turning head 23.

As an instance of the operation of the drums 110 and 111 consider the operation of drum 110. When the brake band 126 of the brake wheel 117 is applied the drum 110 is held stationary or allowed to slowly revolve and the cable 56 unwind. To revolve the drum 110 and wind the cable thereon the brake band 126 can be applied in connection with the wheel 120, consequently said wheel 30 is held stationary and the pinions 123 are driven through the medium of the gear wheel 114, thereby imparting movement to the rack 115 and the drum 110. The brake bands of the wheels 120 and 117 are alternately applied and consequently the operation of the two drums can be controlled to a nicety for moving the bucket 52 in a desired direction.

What I claim is:

45 1. In an excavating machine, a vertically disposed swiveled mast, an upwardly inclined shiftable boom pivotally connected with said mast and capable of being adjusted during the operation of the machine, an upwardly extending member arranged over the boom and pivotally connected at its lower end in proximity to the pivoted end of the boom, a normally inclined yoke having the upper ends of its arms pivotally connected to the upper end of said member above the boom, said yoke depending below said boom, a bucket connected to the lower end of said yoke, a cable connected at one end with said member and capable of retracting the pivot 50 upon which the yoke swings, means for winding said cable to retract said pivot and yoke, and a cable connected to said bucket and extending over the boom for operating a bucket and for moving the yoke relatively to said member.

2. In an excavating machine, a vertically disposed swiveled mast, an upwardly inclined shiftable boom pivotally connected with said mast and capable of being adjusted during the operation of the machine, an upwardly extending member arranged over the boom and pivotally connected at its lower end in proximity to the pivoted end of the boom, a normally inclined yoke having the upper ends of its arms pivotally connected to the upper end of said member above the boom, said yoke depending below said boom, a bucket connected to the lower end of said yoke, a cable connected at one end with said member and capable of retracting the pivot 70 upon which the yoke swings, means for winding said cable to retract said pivot and yoke, and a cable connected to said bucket and extending over the boom for operating a bucket and for moving the yoke relatively to said member, a turning head arranged at the upper end of the mast; and means for operating said turning head to swing said mast, boom, member and yoke horizontally.

3. In an excavating machine, a vertically disposed swiveled mast, an upwardly inclined shiftable boom pivotally connected with said mast and capable of being adjusted during the operation of the machine, an upwardly extending member arranged over the boom and pivotally connected at its lower end in proximity to the pivoted end of the boom, a normally inclined yoke having the upper ends of its arms pivotally connected to the upper end of said member above the boom, said yoke depending below said boom, a bucket connected to the lower end of said yoke, a cable connected at one end with said member and capable of retracting the pivot 90 upon which the yoke swings, means for winding said cable to retract said pivot and yoke, and a cable connected to said bucket and extending over the boom for operating a bucket and for moving the yoke relatively to said member, a turning head arranged at the upper end of the mast; and means for operating said turning head to swing said mast, boom, member and yoke 95 horizontally.

4. In an excavating machine, a vertically disposed swiveled mast, an upwardly inclined shiftable boom pivotally connected with said mast and capable of being adjusted 100 during the operation of the machine, an upwardly extending member arranged over the boom and pivotally connected at its lower end in proximity to the pivoted end of the boom, a normally inclined yoke having the upper ends of its arms pivotally connected to the upper end of said member above the boom, said yoke depending below said boom, a bucket connected to the lower end of said yoke, a cable connected at one end with said 105 member and further for controlling the movement of the bucket independent of the shifting of the yoke pivot, the turning head arranged at the upper end of the mast, and means for operating said turning head to swing said mast, boom, member and yoke 110 horizontally.

- member and capable of retracting the pivot upon which the yoke swings, means for winding said cable to retract said pivot and yoke, and a cable connected to said bucket and extending over the boom for operating the bucket and for moving the yoke relatively to said member and further for controlling the movement of the bucket independent of the shifting of the yoke pivot, a turning head arranged at the upper end of the mast, means for operating said turning head to swing said mast, boom, member and yoke horizontally, and means for swinging said mast independent of the means for controlling the movement of the bucket.
5. In an excavating machine a portable support, a boom having its lower portion pivotally connected therewith, an upwardly extending element arranged above the boom and having its lower end pivoted, a bucket support depending below the boom and adapted to carry a bucket on its lower end, means carried by the upper end of said element to provide a pivot for the upper end of said bucket support, said means capable of being shifted in the arc of a circle, and means connected with said element for shifting the same to vary the scooping scope of the bucket without shifting said portable support simultaneously with the shifting of the boom on its pivot, and means traveling over said boom for operating said bucket, and means for controlling the operation of the bucket independent of the shifting of said pivoted element.
